BIN FOR RECEIVING FAN-FOLD PUNCHED TAPE ON TAPE-USING INSTRUMENTS

George S. Hager, Anaheim, and Joseph B. Dufresne, Apple
Valley, Calif., assignors to Electronic Engineering Com-
pany of California, Santa Ana, Calif.

Filed June 13, 1974, Ser. No. 479,009

Term of patent 14 years

Int. Cl. D14—02

U.S. Cl. D26—5 C

FIG.1.

FIG.2.

FIG.3.

FIG.4.

FIG.6.

FIG.5.

FIG. 1 is a perspective view of a bin for receiving fan-fold punched tape on tape-using instruments, showing our new design, and shown mounted on a perforated tape reader which is shown in broken lines for illustrative purposes only and forms no part of the claimed design;

FIG. 2 is a front elevational view thereof;

FIG. 3 is a rear elevation thereof;

FIG. 4 is a top plan thereof;

FIG. 5 is a bottom plan thereof; and

FIG. 6 is a cross-sectional view thereof, taken along the line 6—6 of FIG. 4.

We claim:

The ornamental design for a bin for receiving fan-fold punched tape on tape-using instruments, as shown.
